MINE CAR

Frederick H. Gibbs, Brooklyn, N. Y., assignor to
 American Car and Foundry Company, New
 York, N. Y., a corporation of New Jersey

Application December 3, 1932, Serial No. 645,545

1 Claim. (Cl. 105—364)

This invention relates to mine cars and has for one object the provision of a mine car body the capacity of which is increased over that of the usual body without increasing the overall dimensions.

It is well understood that the clearance space within which a mine car must travel in a mine is limited. It is highly desirable, in spite of the limited clearance within a mine, to provide a mine car having a body with as great a lading capacity as is possible. In end dump mine cars it is common practice to arrange the bail for the end gate on the outside of the car body. This bail may consist of connected bars or a single plate but in the usual type of mine car body the fact that the bail is arranged on the outside or outer surface of the body means that the interior of the car body is correspondingly reduced in width in order that the mine car may not exceed the clearances provided within a mine. In addition to the bail it is common practice in mine car construction to provide reinforcing elements in the form of belts arranged outside the body and extending across the car bottom and upwardly along the side walls of the car. It is apparent that these belts, in addition to the bail, project beyond the side walls of the car body and this necessitates a reduction in the width of the car body.

Another object of this invention is to provide a mine car body which is reinforced and stiffened by belts or by ties which extend from side wall to side wall and connect the side sills but in which car body the belts do not project or extend beyond the normal vertical plane defined by the side walls of the car whereby it is possible to provide a car body of increased lading capacity without a corresponding increase in the over-all dimensions of said body.

Still another object of this invention is the provision of a mine car body having reinforcing elements for the side walls thereof which are inset with relation to the side walls whereby the width of the car body is increased.

A further object of this invention is the provision of an end dump mine car having an end gate with an outside bail arranged closely adjacent the side walls of the body.

A still further object of the present invention is the provision of a mine car body having its side walls stiffened by means of inset portions so formed that substantially no interference to free dumping of the lading results.

Other objects and advantages of this invention will be apparent from the following description

taken in conjunction with the accompanying drawing in which:

Figure 1 is a side elevation of a mine car showing the body of the present invention.

Fig. 2 is a sectional view on the line 2—2, 60 Fig. 1.

Fig. 3 is a sectional view on the line 3—3, Fig. 1.

Fig. 4 is a sectional view on the line 4—4, Fig. 2, and

Fig. 5 is an end elevation of the car body. 65

Referring now more particularly to the drawing in which similar characters of reference designate similar parts in the several views, the car of the present invention comprises a body indicated generally at A, supported by wheels B, 70 carrying stub axles C. While the car shown is of the stub axle type it is not to be understood that the invention is limited thereto as the car may have axles which are arranged either above or below the plane of the car floor or bottom and 75 which carry wheels at the opposite end portions thereof. All of this will be apparent from the description to follow.

The car body A is substantially rectangular in plan and comprises a central floor portion 2 the 80 side edge portions of which are upwardly and then outwardly flanged as at 4 and 6 respectively to form side sills integral with said central floor portion. If desired it is apparent that the side sills may be formed as independent elements to 85 which the central floor portion 2 may be secured. Extending outwardly from the upper sill flanges 6 are side floor portions 8 which, in the instance shown, are formed integral with the side walls 10. The upper edge portions of the side walls 90 are stiffened by a bead 12. Obviously within the spirit of the present invention, the side walls 10 may be independently formed and attached or secured to the side floor portions 8 in any suitable or desired manner. One end of the 95 body is provided with a fixed end wall 14, stiffened by a bead 15 while the opposite end is closed by a gate 16. The car of the present invention is provided with bumper constructions 18.

As before mentioned, it is desirable to provide 100 a mine car with a body having as large a lading capacity as is possible within the clearance limits afforded in a mine. To effect this the body is made as wide as possible and the side walls thereof are provided with a plurality of vertically arranged recesses 20 formed by insetting the side walls 10 for a portion of their height as shown at 22. The recesses 20 extend upwardly from the side floor portions and terminate below the bead 12. As clearly shown in Figs. 3 and 4 the re- 110

cesses terminate a substantial distance below the beads 12 and, as shown clearly in Fig. 2, they are of a depth sufficient to receive the vertical portions of belts 24 in such a manner that the latter do not project or extend beyond the vertical plane of the outer surfaces of the side walls 10. The inset portions are formed with unequal sides 26 and 27 which are relatively so arranged that they do not interfere with the discharge of the lading from the car, in fact, the arrangement of said sides facilitates discharge of the lading; side 26 sloping gradually inwardly relative to the car body and toward the gate end while the side 27 of each inset portion has an abrupt slope, all as clearly shown in Fig. 2.

The belts 24 are secured in any suitable manner as by rivets 28 within the recesses 20 and extend under the side floor portions and against the side sills S and then downwardly under the central floor portion 2. The belts may be and preferably are secured to the floor portions 2 and 8 in any suitable manner as by rivets 30.

The gate 16 is provided with a bail 32 formed in the instance shown of a pair of connected bars, though obviously this bail may be a single plate if desired. The bail 32 is pivotally connected by means of a pin 34 to one of the belts 24 so that the body may be tilted and the gate supported to open the end of the body for dumping purposes. It is apparent that due to the insetting of the belts 24 the bail 32 is brought closely adjacent the side wall 10 (see Fig. 2) and therefore, in case of undue stress at the dumping end of the car against the side walls 10, serves as a means for preventing bulging of the side walls. For stiffening purposes the end gate 16 is provided with suitable rigidifying corrugations or embossments 36.

The side floor portions are provided with wheel receiving openings which are covered by wheel housings 38 which, in the instance shown, are pressings adapted to be applied to the car by insertion through the opening from below; the housings 38 including attaching portions 40 and having bearing portions 42 which support the stub axles C. The outer bearing portion 42 is reinforced by a bracing member indicated in Fig. 2 at 44.

From the description given above it is obvious that due to the inset of the side walls of the car body A the belts 24 do not project beyond the vertical plane of the side walls 10. This provides a construction in which the width of the car may be increased with a resulting increase in

lading capacity. The construction also provides an arrangement in which the bail 32 lies closely adjacent the side walls 10 of the car and this bail may be made of relatively thin gauge material commensurate with service conditions. The width of the body is increased to an appreciable extent and the full lading capacity of said body is thus maintained. In a typical example, a body which is approximately ten feet long and which has side walls approximately two feet high, the width of said body is increased, with a resulting increase in capacity of approximately two cubic feet and this is effected by no increase in the overall dimensions of the car.

As will be observed in Fig. 2 the end belt providing vertical post portions 24 next the end gate 16 is positioned wholly within the normal outer plane of the side wall at that end of the car body and the sloping surface 26 inclines inwardly of the body towards the end gate at an angle of about thirty degrees from the normal plane of the side wall, thereby forming, with the end gate, a housing for the end belt 24 provided with such gradually sloping surface within the car body as to provide little or no obstruction to the flow, by gravity, of the coal to be dumped from said body. A somewhat similar condition exists at each belt 24 at which the face 26 farther from the end gate is more gradually inclined than is the more abrupt slope at the opposite side of the recesses 20.

The drawing herein illustrates one embodiment of the invention but it is to be understood that it is for illustrative purposes only and various changes in the form and proportions of the construction may be made within the scope of the appended claim without departing from the spirit of the invention.

What is claimed is:

In an end dump mine car, a body comprising side walls and an end gate, said side walls having portions thereof inset to provide external vertical recesses and internal wall stiffeners, said stiffeners each having a part thereof which slopes gradually inward relative to the body in a direction toward the end gate whereby to facilitate discharge of lading from the body, belts extending under the car body and into said recesses, and a bail for the end gate pivoted to one of said belts and arranged closely adjacent portions of the outer surfaces of said side walls whereby to serve as reinforcements therefor.

FREDERICK H. GIBBS.
